UNITED STATES PATENT OFFICE.

JAMES C. MEEM, OF BROOKLYN, NEW YORK, ASSIGNOR OF TWO-THIRDS
TO BOROUGH CONSTRUCTION COMPANY, OF BROOKLYN, NEW YORK,
A CORPORATION.

APPARATUS FOR EXCAVATING TUNNELS.

No. 819,443.

Specification of Letters Patent.

Patented May 1, 1906.

Application filed October 11, 1905. Serial No. 282,300.

To all whom it may concern:

Be it known that I, JAMES C. MEEM, a citizen of the United States, residing at Brooklyn, in the county of Kings and State of New York, have invented a new and useful Apparatus for Excavating Tunnels, of which the following is a specification.

This invention relates to apparatus for excavating tunnels, and constitutes an improvement upon one of similar character which is shown in a United States Patent granted to me for a method of tunneling, dated June 16, 1903, No. 731,198.

The object of the present invention is to provide a tool in the nature of a sectional roof or side shield for tunneling in which each section shall be capable of being operated independently of the others, to facilitate making of excavations, and in a pronounced manner to insure the safety of the operators.

With the above and other objects in view, as will appear as the nature of the invention is better understood, the same consists in an apparatus for tunneling, as will be herein-after fully described and claimed.

In the accompanying drawings, forming a part of this specification, and in which like characters of reference indicate corresponding parts, Figure 1 is a view in elevation, exhibiting the manner in which the apparatus of the present invention is supported when in position. Fig. 2 is an end view of one of the sections of the apparatus. Fig. 3 is a view in side elevation, partly in section, of one of the implements. Fig. 4 is a view in side elevation, partly in section, showing a slightly modified form of the invention. Fig. 5 is a view in side elevation of another modified form of the invention. Fig. 6 is a transverse sectional view through the form of invention shown in Fig. 5.

In constructing a tunnel with the implement of the present invention two, three, four, or more of these may be employed, and as each is a counterpart of the other a description of one will serve for all. The implement or tool embodies a pair of bearing-beams 1, a plurality of cross-bars 2—in this instance three in number—and a plurality of cover-plates 3—in this instance three in number. The bearing-beams and cross-bars are preferably made of wood or steel and may be of any desired length or breadth, and the cover-plates are

made of structural iron or steel or iron and steel combined with wood and extend some distance in front and in rear of the bearing-beams to form a nose-piece 4 and a tailpiece 5, the latter being by preference projected rearwardly beyond the bearing-beams a greater distance than the former project beyond the same. As herein shown, the cover-plates are preferably hollow rectangles, and each is provided with two inturned flanges 6, through which pass bolts or rivets 7, that secure them to the cross-bars, the webs and internal flanges being preferably cut away under the tailpiece, as shown in Figs. 3, 4, and 5. The cover-plates of each section or implement have their webs connected by bolts or rivets 8, whereby they are held rigidly assembled and are prevented from having any movement relatively to each other. The bearing-beams 1 are secured to the cross-bars by bolts 9, the heads of which are socketed in the cross-bars and the lower ends of which are disposed in sockets 10 in the under faces of the bearing-beams and carry nuts 11, by which the parts are held positively combined. The sockets 10 are of such depth that when the nuts 11 are seated they, as also the lower ends of the bolts, will lie within the plane of the under face of the bearing-beams, and thus obviate the presentation of obstructions or projections that would be objectionable.

Intermediate of their ends each pair of bearing-beams has secured to it a lug or abutment 12, which is preferably made of double-L angle-iron and is attached to the bearing-beams by bolts 13 and nuts 14.

In order to obviate digging under the nose-piece of the implement, means is provided by which water under pressure may be driven either under or ahead of the nose-piece, and this is secured by the employment of a nozzle 15, arranged beneath the cover-plate and with which is connected a hose 16, leading to a suitable supply of water under pressure. This arrangement will be found of great advantage where excavations are being made in light or sandy soil, as the water will wash the earth out more rapidly than it could be excavated by hand.

In using the implement as shown in Fig. 1, in which four of the tools are employed, base-beams 17 are provided, upon which rest the lower ends of blocking-beams 18, the upper

ends of which support segment-beams 19, upon which the implements rest. As above stated, each implement is operable independently of the other, and their movement forward is effected by means of hydraulic jacks, which engage the abutments 13 in the same manner as that described in connection with the patent referred to. As the implements are moved forward by the hydraulic jacks permanent lagging may be positioned, or the permanent tunnel itself may be built under the tailpieces 5, so that as the tool advances the superposed earth may rest upon the lagging or tunnel itself, as preferred. By the employment of water under pressure the forward movement of the implements is facilitated and the earth washed away thereby may be removed in any preferred manner.

In the patent referred to the jacks are detachable from the abutments; but, if preferred, they may be rigidly secured thereto, as shown at 20 in Fig. 4, and thereby facilitate the operation of tunneling, as the loss of time incident to the misplacing of the jacks, which frequently occurs, will be effectually obviated.

In the form of the invention shown in Figs. 2 and 3 the spaces between the cover-plates 3 are left open; but, if preferred, these spaces may be filled with timber or metal 21, as shown in Figs. 5 and 6, in which case the cover-plate 22 may be a plain flat plate bolted to the filler 21, and I-beams 23 may be substituted for the wooden bearing-beams, as shown in Fig. 1. When the fillers are used in conjunction with the cover-plate, the hydraulic pipe will project under the nose-piece through a slot or groove cut in the cover-board.

As a matter of further improvement there may be combined with the implement a supplemental excavating-tool, which may be substituted for jet pipes or nozzles, if desired, or may be used in conjunction therewith. This tool, as shown in Figs. 5 and 6, consists of a bar of metal 24, having at one end a handle 25 and at its other end an excavating-point 26, which is normally disposed beneath the nose-piece. As shown in Fig. 5, the tool is suspended from a suitable hanger 27, secured in any preferred manner to the forward end of the bearing-beam and is adapted for reciprocatory movements therein, while in the form of the invention shown in Fig. 6 the tool is suspended from a hanger 28, combined for swinging movements with the cover-

plate. Of these supplemental tools there may be any number, and as this will be readily understood detailed illustration of more than one is omitted.

Generally it will be preferred to employ jacks of the hydraulic type for moving the implements forward; but it is to be understood that any other power may be employed that may be found available and advantageous.

Having thus described the invention, what is claimed is—

1. A tool for tunneling consisting of a roof-shield comprising a plurality of independently-adjustable sections, and means combined with each section for introducing water under pressure under or ahead of the tool, and in the direction of its length.

2. A tool for tunneling consisting of a roof-shield comprising a plurality of independently-adjustable sections, means combined with each section for introducing water under pressure under or ahead of the tool and in the direction of its length, and excavating mechanism associated with the noses of the sections.

3. An implement for tunneling comprising a plurality of bearing-beams, cross-beams secured thereto, a plurality of cover-plates extending beyond the terminals of the bearing-beams, the extended portions constituting nose and tail pieces respectively, means combined with each of the cover-plates for introducing water under pressure under or ahead of the nose-pieces and in the direction of their length, excavating means assembled with the nose-pieces, and means for projecting one of the cover-plates independently of the others.

4. An implement for tunneling comprising a plurality of bearing-beams, cross-bars secured thereto, a cover-plate extending beyond the terminals of the bearing-beams, the extended portions of which constitute nose and tail pieces respectively, and means associated with the implement for introducing water under pressure under or ahead of the nose-piece and in the direction of its length.

In testimony that I claim the foregoing as my own I have hereto affixed my signature in the presence of two witnesses.

JAMES C. MEEM.
